PARACHUTE SHROUD LINE SUSPENSION
STRUCTURE

Leonard P. Frieder, Great Neck, and Walter S. Finken, Brooklyn, N. Y., assignors, by mesne assignments, to Reconstruction Finance Corporation, Philadelphia, Pa., a corporation of the United States

Application January 25, 1950, Serial No. 140,424

10 Claims. (Cl. 244—145)

1

This invention relates to parachutes and more particularly to shroud line suspension structure for parachutes, i. e. arrangements whereby the shroud lines, which usually converge to one or more points for suspension of the load, are connected to the canopy of the apparatus for transmission of the load-retarding force. In a more particular sense, the invention is directed to improved parachute rigging or shroud-line-suspending arrangements of the type involving a hem cord, e. g. a continuous cord encircling the hem of the parachute and enclosed within a hem sleeve or equivalent structure, whereby strain is transferred from the shroud lines in a somewhat distributed manner to the lower edge of the fabric canopy. Examples of prior structures of this type are as embodied in our Patent No. 2,365,184, granted December 19, 1944, for Parachute, and likewise as shown in Patent No. 2,412,392, granted December 10, 1946, for Parachute, on the application of Walter S. Finken. Such arrangements, for example, include a hem cord traversing a continuous sleeve around the edge of the canopy, the sleeve having openings at peripherally spaced localities for access to the cord, and the upper ends of the shroud lines being directly connected to the cord, as by a loop around the cord at each opening.

An important object of the present invention is to provide improved suspension structures of the character described, affording greater or more complete distribution of load stress along the lower edge of the canopy, while achieving an effective and secure support of the load. A further object is to provide a suspension structure whereby the load supporting connections at the hem edge of the canopy may be of an appropriately large number, spaced around the edge, and thus may afford effective distribution of stress throughout the canopy fabric, while the shroud lines may be of a reduced or small number so as to minimize the possibility of shroud line entanglement and so as to permit economy of stowage space, i. e. for stowing the parachute in its packed condition while it is being carried aloft prior to use.

A further object is to provide a suspension system for parachutes, wherein the maximum points of strain exerted on the canopy edge by the shroud lines may be multiplied, as desired, from the number of such lines, for greater distribution of force upon the canopy fabric. Another object is to provide new and improved apparatus of the character stated, particularly adapted for a canopy of the hemispherical type, wherein

2

opening or deployment of the canopy is facilitated; a still further object is to provide structure thus enhancing the opening, or any desired constricting, of the canopy, such structure avoiding frictional and like resistance to the proper enlargement or other displacement of the canopy hem to its intended, operative diameter. It may be explained that hemispherical parachute canopies tend to bloom or open through successive stages, the earlier stages involving a pear-shaped or other elongated configuration wherein the hem edge of the canopy is contracted to a substantially smaller diameter than that finally desired and permitted by the actual fabric dimensions. The arrangements of the present invention are useful for other types of canopies, especially for other shaped canopies wherein some advantages of a true hemisphere are sought by means of a skirt or like structure arranged with an upper portion which may resemble the corresponding part of a so-called flat type canopy.

Other objects are to provide improved apparatus of the character described, wherein maintenance of the several lines and connecting parts in their desired relationship is promoted and wherein lateral displacement of a shroud or other load-supporting line is obviated, a further, specific object being to provide novel and effective means for preventing such lateral displacement of a connecting loop along a cord which supports it.

To these and other ends, certain presently preferred embodiments of the invention are described below and set forth in the accompanying drawings, by way of example, to illustrate the features and principles of improvement.

Referring to the drawings:

Fig. 1 is a diagrammatic view of a load-carrying parachute, embodying one form of suspension in accordance with the present invention;

Fig. 2 is an enlarged view of a portion of the hem region of the parachute in Fig. 1;

Fig. 3 is a fragmentary view showing the configuration of the canopy edge and line structure prior to full deployment;

Fig. 4 is a view, similar to Fig. 2, illustrating another embodiment of the present improvements;

Fig. 5 is a fragmentary view illustrating the embodiment of Fig. 4 with the parachute in partially deployed condition;

Fig. 6 is a view, similar to Fig. 1, of a further structure according to the invention;

Fig. 7 is a view like Figs. 2 and 4, showing the device of Fig. 6;

55

Fig. 8 is an enlarged, fragmentary illustration of the cord and line arrangements in Fig. 7; and Fig. 9 is a fragmentary view, similar to Fig. 3, illustrating the structure of Fig. 7 before the canopy is fully deployed.

As indicated above, an effective prior arrangement for shroud line suspension has involved a so-called floating hem cord, to which the shroud lines are directly attached, through openings in the hem sleeve, at points correspondingly spaced around the edge of the canopy. While the floating hem cord serves to distribute a substantial portion of the stresses along the hem line of the canopy, localized stress or pull of considerable extent nevertheless occurs at the localities of the canopy adjacent such openings, i. e. transmitted by the cord, which itself is subjected to the completely localized downward stress of the shroud lines at such localities. While such arrangements are nevertheless effective, the adaptation of parachutes for support of heavier loads and for discharge at very high air speeds, tends to increase the stresses on the canopy, both during inflation and thereafter, and the present invention is therefore designed (as explained above) to afford greater or better distribution of load stress and to permit effective parachute construction with canopies of minimum strength fabric.

With devices of the sort shown in the patents cited above, for example as in Fig. 15 of the Finken Patent No. 2,412,392 and Figs. 1 and 3 of our Patent No. 2,365,184, the preliminary opening stages of a hemispherical canopy involve the withdrawal of the hem cord into a depending loop, i. e. at each sleeve opening, under the pull of the corresponding shroud line. The hem sleeve and adjacent regions of the canopy are then correspondingly gathered or Shirred, so as to occupy a much shorter distance along the hem cord between successive openings. Subsequent extension of the hem edge to the desired, full diameter, requires the retraction of the cord from the depending loops into the sleeve. Considerable frictional resistance is exerted in the last-mentioned operation, thereby increasing the amount of work which must be performed by the canopy, relative to the load, in the final stages of deployment.

Although this additional work is of no disadvantage under many circumstances the situation of heavy loads and high air speeds makes it desirable to minimize all forces acting on the canopy or required to be overcome in the canopy-deploying operation. While Fig. 4 of the cited Patent No. 2,365,184 shows one structure which avoids the frictional problem last stated and while in our copending application Serial No. 122,962, filed October 22, 1949, we have shown that the problem may also be avoided in the devices of the cited patents by bar-tacking or otherwise securing the hem cord to the sleeve at the edges of each opening, the structures hereinbelow described afford an improved arrangement for such purpose, particularly in combination with features otherwise of structural advantage.

It will be understood that a hemispherical canopy, to which the present invention is particularly related, is a canopy wherein the several constituent pieces of fabric are so cut and joined together that the parachute on deploying assumes a substantially truly hemispherical shape, as distinguished from so-called flat or parabolic canopies. One form of hemispherical parachute is shown, for example, in the above cited Patent No. 2,412,392.

Referring now to Figs. 1, 2 and 3, the illustrated

apparatus of the present invention includes a hemispherical canopy 10, which is composed, for instance, of a crown section 11, and a circumferential series of fabric gores 12 joined at their substantially vertical edges, and which is intended to support a load 14 by shroud lines 16, the bottom or hem edge of the canopy being designated 18. Along the latter edge, the canopy has a hem sleeve 20 adapted to receive a hem cord 22, i. e. extending peripherally around the bottom edge of the canopy as more particularly described below.

The hem sleeve has a plurality of openings 24 spaced regularly around the hem edge, and preferably disposed at intermediate regions of the canopy gores, i. e. avoiding coincidence with vertical seams. While in the arrangement of the previously cited patents, the hem cord is completely enclosed by the sleeve 20 and there is a shroud line connected to the hem cord through each opening, the arrangement of Fig. 2 involves the alternate disposition of the hem cord through portions 20a of the hem sleeve and in an outside relation to the hem at portions 20b thereof. Thus the hem cord passes in and out through successive openings 24, so that the portions 22a of the hem cord are enclosed in sleeve portions 20a while portions 22b of the hem cord extend outside of the canopy, between successively spaced pairs of openings 24. The shroud lines 16 are directly connected to the external bridging or ratline portions 22b of the hem cord, for example by providing the upper end of each shroud line with a loop 25 which encircles the cord.

By this arrangement a decreased number of shroud lines is permitted, yet the distribution of strain to the canopy is effective in equal amount and location to the arrangement of the prior patent, i. e. where there is a shroud line connected to the hem cord at each opening in the sleeve. While the only sleeve portions actually utilized in the structure of Figs. 1 to 3 are the portions 20a, and there is thus no necessity for an actual sleeve at the regions 20b, the drawings indicate such structure as representing simplicity and uniformity in manufacturing operation.

A particular advantage of the arrangement shown in Figs. 1 to 3 is that when the canopy begins to inflate, and its bottom edge is preliminarily contracted to a small diameter under the initial shock or weight of the load, the spaces 20b of the canopy edge and lower portion simply assume the shape of a large pleat or fold, as indicated in Fig. 3: Thus each loop 22b of the hem cord is pulled downward in the manner shown, bringing adjacent openings 24 close together, and forming the stated pleat or fold. Thereafter, expansion of the hem edge of the canopy to its intended diameter simply involves the upward movement of each shroud line relative to the bottom edge of the canopy, so as to more nearly straighten out the loops 22b. There is no frictional loss occasioned by pulling the cord relative to the sleeve, since the cord is wholly free of the canopy fabric at the region 22b. Thus prompt and complete opening of the canopy is greatly facilitated.

The effect just described is enhanced by provision of suitable means to prevent lateral displacement of the cord in the sleeve portions 20a, adjacent the openings 24. Thus, for example, suitable stitching or bar-tacking 26 may be employed, sewing the sleeve faces together through the cord 20 at the stated localities. It is thereby fully insured that the downward pull on the line por-

tions 22b at the outset of deployment will fail to withdraw the cord to any extent from the sleeve portions 20a. There is thus no possibility at all, of shirring or gathering of the fabric, and consequently no frictional force to be overcome in the final stages of canopy deployment. Indeed the sleeve portion 20a may itself, in some cases, form a single pleat or fold of the same sort indicated at 20b in Fig. 3.

Another arrangement is illustrated in Figs. 4 and 5, where the canopy 30, represented by portions of two of its gores 31 and having a bottom edge 32, is provided with a similar hem sleeve 34. A hem cord 36 likewise extends completely around the hem edge of the canopy, but in this instance is fully enclosed within the hem sleeve except for accessibility at the regularly spaced openings 38 in the sleeve. A supplemental line or cord 40 is likewise arranged to encircle the canopy at the bottom, but conveniently outside the hem sleeve 34. The cord 40 is looped or woven over the hem cord 36 at each of the openings 38, e. g. by simply passing over the cord 36 in the same direction at each successive opening. Thus the cord 40 is maintained in place by the hem cord 36 and constitutes, in effect, a succession of ratline or suspended cord portions or loops intermediate successive openings 38. To each alternate portion 40a of these external cord portions, one of the shroud lines 41 may be connected, as by means of a loop 42 surrounding the cord.

Thus in the arrangement of Fig. 4, there is a shroud line 41 for each pair of connections to the hem cord 36. In consequence essentially the same advantages are obtained, i. e. in permitting a reduction in the number of shroud lines, or alternatively, in providing a greater distribution of spaces of localized supporting stress on the canopy around its bottom edge. Like bar-tacking 44 may also be employed in the arrangement of Figs. 4 and 5, to secure the hem cord 36 against lateral displacement in the hem sleeve 34 at both edges of each of the openings 38. Under such circumstances, the preliminary retracted condition of the hem edge of the canopy as it starts to open, will involve the folding of the edge and lower canopy portion into single large pleats or folds as represented at 45 in Fig. 5. Such pleats or folds will at least occur in the canopy portions bridged by the ratline portions 40a, and usually also in the intermediate spaces 46 (Fig. 4) of the canopy edge, i.e. between the other, alternate pairs of openings 38. In consequence frictional resistance is essentially avoided in the final deployment of the canopy to its full, intended shape.

While the arrangement of Figs. 4 and 5 is eminently useful, the structure of Figs. 1 to 3 is of some present preference for heavier duty as well as for simplicity of structure. It will be noted that in Figs. 4 and 5 there may be some small frictional effect of the external cord 40 across the small loops of the hem cord 36 at the openings, especially if pleats are formed in regions 46 of the canopy edge.

A further and especially preferred arrangement is illustrated in Figs. 6 to 9 inclusive, where a like hemispherical canopy 50 is shown, having a crown section 51 and side gores 52, terminating in a bottom edge 54. Again a hem sleeve 55 is provided adjacent the bottom edge, enclosing a continuous hem cord 56 which is accessible through successive, regularly spaced openings 58 along the sleeve. Successive, spaced pairs of the openings 58 are bridged by separate, external cord portions 60, which are conveniently connected to

the hem cord 56 by loops 61 at their respective ends, i.e. in the successive openings 58. The shroud lines 62 of the parachute are connected respectively to the external cord portions 60, e.g. by loops 63 at the ends of the shroud lines. It is thus seen that the portions 60 thus bridge successive, spaced canopy edge portions 54a, being separated, successively around the canopy by intermediate edge portions 54b, which may be of similar length. In consequence, the number of localized regions of stress on the canopy is increased relative to the number of shroud lines, affording a great distribution of stress on the canopy gores, as clearly apparent in Fig. 6.

The arrangement of Fig. 7 may likewise include bar-tacking 64, securing the hem cord 56 in the sleeve 54 at each side of each opening 58, preventing lateral displacement of the cord in the sleeve and thus permitting the retracted condition of the canopy edge to assume single large folds, e.g. as shown at 65 in Fig. 9, at the portions bridged by each ratline 60, and indeed similarly at the intermediate portions 54b in many instances.

As shown more particularly in Figs. 8 and 9, the arrangement of these views includes means (means of similar purpose being also applicable to corresponding parts of other embodiments of the invention, if desired) for preventing sidewise movement or slippage of the shroud line connection 63 along the external or ratline cord portions 60. In Figs. 8 and 9, the specific arrangement involves the constitution of the ratline portions 60 from tubular, braided cord, i.e. having a hollow center. Each of the loops 61 constitutes a bight in the cord, having a further end portion 67 which is brought into the hollow center of the standing part of the cord 60, being threaded through the strands of the cord wall at the vicinity 68 of the loop, the end portion 67 having sufficient extent to reach nearly to the center 69 of the ratline portion 60.

Thus for the major part of its length at either side of the shroud loop, the cord 60 is considerably thickened by the reentrant end portion 67, leaving a thin zone or section at the center 69, of considerably smaller diameter, which is preferably snugly fitted by the loop 63 of the shroud line 62. It will be understood that the loop 63, as likewise other loops herein disclosed, may be achieved by telescopically splicing the end 64 of the tubular cord of which the shroud line is made, into the center of the standing part of the shroud line. Thus by the construction of Figs. 8 and 9, preferably achieved by the telescopic splicing of the loop end 67 within the cord portion 60 at each end of the latter and throughout nearly all of the distance to its center point 69, the loop 63 is kept at the center locality, against sliding over the thicker portions.

As will now be apparent, the arrangement of Figs. 6 to 9 inclusive, has the advantages of the structures in the preceding figures, particularly in distribution of load force along the hem of the canopy and in affording a strong and reliable support of the load while permitting the use of fabric of minimum weight and strength for the canopy 50. Frictional resistance is obviated in opening or retraction of the canopy hem, as by forming folds in the manner indicated in Fig. 9 rather than the pleated or shirred condition of a hem sleeve around a hem cord. A complete hem cord is provided for its own force-distributing effect at all localities intermediate the openings or points of connection 58, yet by the separate ratline portions 60, effective distribution from the shroud

line 62 is provided. While further concentration of the stresses between the canopy and the shroud lines may be effected (in similar fashion to the arrangements herein shown) by supplemental or additional, intermediate ratline structures, the systems shown in the drawings are peculiarly effective for the described purpose and constitute practical and efficient shroud line supports for a wide variety of types and uses of parachutes.

The devices are of cooperative advantage in facilitating the so-called skirting or incurving effect at the hem line of the parachute, which is specifically pointed out in Fig. 1, but which may be characteristic of the other arrangements as well. That is to say, whereas the full or intended form of the parachute may be a complete hemisphere, having a semi-circular contour at the lowermost edges as represented by the dotted lines 70, operation under load (especially heavier loads or higher air speeds) tends to retract the hem edge 18 of the canopy to a slightly smaller diameter so that the region immediately adjacent the edge, e. g. extending upward for several inches, curves inwardly as indicated at 71. This incurving or skirting configuration of the deployed canopy has been found to contribute materially to the stability of the structure in flight, i. e. after it is bloomed and when it is serving its load-retarding function. Oscillation of the canopy, spilling of air and like effects are greatly reduced, yet without appreciable sacrifice of buoyant force. The essentially friction-free system of the present devices, i. e. structures wherein expansion and retraction of the hem edge may occur simply as a resultant of the forces exerted by the canopy, load and air stream, and without hindrance due to frictional effects of a hem cord in a sleeve or the like, permit full realization of the described incurving effect. The hem edge of the canopy, in other words, is entirely free to assume the configuration 71 shown in Fig. 1, with its described advantages. As indicated, improvement in this respect is similarly characteristic of the other devices herein illustrated, particularly including the device of Fig. 6.

It is to be understood that the invention is not limited to the specific apparatus herein shown and described, but may be embodied in other forms without departure from its spirit.

We claim:

1. In a parachute, the combination, with a canopy having a hem edge, of a shroud line suspension structure comprising a plurality of loop-forming line portions arranged in association with the canopy around its hem edge to constitute loops projecting from said edge, the ends of each loop being spaced so that the loop tends to exert tension on the canopy at corresponding spaced localities and the adjacent ends of successive loops being spaced along the hem edge, so that all of said localities are successively spaced, a plurality of suspension line portions respectively connected to the loops to exert downward pull at a central region of each loop, a hem sleeve around the said hem edge of the canopy, a hem cord supported in said sleeve, said sleeve having openings at the aforesaid localities respectively, through which said hem cord is accessible, and said structure including a supplemental cord arranged to encircle the canopy adjacent the hem edge, said supplemental cord lying outside the hem sleeve but passing over the aforesaid hem cord at each of the aforesaid openings, the portions of said supplemental cord intermediate successive, spaced pairs of openings 75

thereby constituting the aforesaid loop-forming line portions.

2. In a parachute, the combination, with a canopy having a hem edge, of a shroud line suspension structure comprising a hem sleeve around said hem edge, said sleeve having openings successively spaced around the hem edge, each opening being spaced from the openings nearest it by corresponding portions of the sleeve, a hem cord disposed within said hem sleeve all the way around said hem edge, said hem cord being supported by all of said sleeve portions, a plurality of separate cords disposed externally of the sleeve around the hem edge and each constituting a loop projecting from the hem edge, each said separate cord being connected at its ends to the hem cord at corresponding spaced openings of the hem sleeve which are separated by one of the sleeve portions and which are each separated from the next adjacent end of a loop-constituting cord by one of the sleeve portions, and a plurality of suspension line portions respectively connected to said separate loop-constituting cords to exert downward pull at a central region of each said separate cord, said structure including means adjacent each opening, at each side thereof, for securing the hem cord against lateral displacement in the sleeve, each of said last-mentioned separate cords including thickened portions respectively extending from the ends thereof to a locality at the center of the cord, the suspension line portion connected to the said cord having a loop snugly encircling the cord at its center intermediate the thickened portions, said thickened portions thereby preventing lateral displacement of the suspension line portion along the cord.

3. A parachute as described in claim 2, wherein in each of said separate cords is constituted of tubular fabric, and has a terminal loop at each end for connecting it to the aforesaid hem cord, each said thickened portion being constituted by an extended portion of the said cord, beyond each said terminal loop, telescopically disposed within the standing part of the cord adjacent the terminal loop.

4. In rigging for a parachute or the like, a supporting cord connected at its ends to horizontally separated points of support, a suspension line portion having a loop around the cord which connects the line portion to the cord at a predetermined intermediate locality of the cord, said cord having thickened portions respectively extending along it away from points adjacent said locality, said thickened portions preventing sidewise displacement of the aforesaid suspension line loop away from said locality.

5. Rigging as described in claim 4, wherein said cord is constituted of tubular fabric, and has a terminal loop at each end for connecting it to the corresponding point of support, each said thickened portion being constituted by an extended portion of the said cord, beyond each said terminal loop, telescopically disposed within the standing part of the cord adjacent the terminal loop.

6. In a parachute, the combination, with a canopy having a hem edge, of a shroud line suspension structure comprising a hem sleeve around said hem edge, said sleeve having openings successively spaced around the hem edge, each opening being spaced from the openings nearest it by corresponding portions of the sleeve, a plurality of external loop-forming line portions disposed around the hem edge to constitute

loops projecting from said edge, each loop-forming line portion extending from a pair of said spaced openings of the sleeve so that the loop ends are separated by a sleeve portion, and the said sleeve openings at the ends of each loop being spaced from the sleeve openings at the ends of adjacent loops by sleeve portions, sleeve-supported line portions in all of said last-mentioned sleeve portions connecting the ends of their adjacent loop-forming line portions for support of the loops, and a plurality of suspension line portions respectively connected to the loops to exert downward pull at a central region of each loop, each of the said sleeve-supported line portions being disposed within and along and being supported by the sleeve portion which encloses it, and each said last-mentioned sleeve portion having means at its ends, adjacent the openings at such ends, for securing the enclosed, sleeve-supported line portion against lateral displacement in the sleeve.

7. A parachute as described in claim 6, which includes a hem cord extending completely around the hem edge inside said sleeve and comprising portions which constitute said sleeve-supported line portions, each of said loop-forming line portions comprising a cord element attached at its ends to the hem cord at respectively spaced openings of the sleeve, and the aforesaid line-portion-securing means being means adjacent each opening, on the side thereof opposite to the direction in which the related loop-forming cord portion extends to another opening, for securing the hem cord against lateral displacement in the hem sleeve.

8. A parachute as described in claim 6, which includes a continuous hem cord encircling the canopy at the hem edge, said sleeve-supported line portions and said external loop-forming line portions constituting alternately successive portions of said encircling hem cord, and the aforesaid line-portion-securing means being means adjacent each opening, on the side thereof opposite to the direction in which the related loop-forming cord portion extends to another opening, for securing the hem cord against lateral displacement in the hem sleeve.

9. In a parachute, the combination, with a canopy having a hem edge, of a shroud line suspension structure comprising a hem sleeve around said hem edge, said sleeve having openings successively spaced around the hem edge, each opening being spaced from the openings nearest it by corresponding portions of the sleeve, a hem cord disposed within said hem sleeve all the way around said hem edge, said hem cord being supported by all of said sleeve portions, a supple-

mental cord similarly extending around the hem edge outside of the sleeve, said supplemental cord being laced over the hem cord at each of the aforesaid openings; said supplemental cord thus constituting successive supplemental cord portions respectively extending between the openings, every other such supplemental cord portion along the hem edge constituting a projecting loop-forming cord portion, and a plurality of suspension line portions respectively connected to said loop-forming cord portions to exert downward pull at a central region of each loop-forming portion.

10. In a parachute, the combination, with a canopy having a hem edge, of a shroud line suspension structure comprising a hem sleeve around said hem edge, said sleeve having openings successively spaced around the hem edge, each opening being spaced from the openings nearest it by corresponding portions of the sleeve, a hem cord disposed within said hem sleeve all the way around said hem edge, said hem cord being contained within and supported by all of said sleeve portions, a plurality of separate cords disposed externally of the sleeve around the hem edge and each constituting a loop projecting from the hem edge, each said separate cord being connected at its ends to the hem cord at a corresponding pair of the spaced openings of the hem sleeve which are separated from each other by one of the sleeve portions and each of which is spaced and separated, by a sleeve portion, from the next adjacent end of the next adjacent one of said separate loop-constituting cords, and a plurality of suspension line portions respectively connected to said separate loop-constituting cords to exert downward pull at a central region of each said separate cord.
